ATTORNEY

UNITED STATES PATENT OFFICE.

CARL A. TORNBERG, OF MARATHON, FLORIDA.

WRENCH.

1,106,752.

Specification of Letters Patent. Patented Aug. 11, 1914.

Application filed October 22, 1913. Serial No. 796,580.

To all whom it may concern:

Be it known that I, CARL A. TORNBERG, a citizen of the United States, residing at Marathon, county of Monroe, and State of Florida, have invented certain new and useful Improvements in Wrenches, of which the following is a specification.

This invention relates to wrenches, and may be more particularly identified with that class of wrenches known as ratchet wrenches.

The primary object of my invention is to provide a wrench of such construction as may be efficiently employed in the adjustment or removal of nuts to or from bolts so positioned as to render the same inaccessible to the ordinary wrench.

A further object of my invention is to provide a wrench of this character equipped with means for rendering the same applicable to nuts of different sizes.

A still further object of my invention is to provide a wrench for attaining these ends which is of such construction as to permit of a maximum amount of power being imparted to the nut engaging means forming a part thereof.

A still further object of my invention is to provide a wrench of the character set forth which is simple in construction, composed of but few parts, which may be disjoined when not in use to occupy but little space for convenience in packing or storing, and yet which, when assembled for operation, will prove a most powerful instrument; the construction and arrangement of the several parts which go to make up the complete instrument being such that in the event of breakage or of the wearing out of any of the various parts, the same may be replaced at very low cost and may be easily and quickly applied to the instrument.

With these objects in view, together with others which will appear as the description proceeds, my invention consists in a stock substantially small in diameter and of a length to be easily manipulated and held in the hands, nut engaging means at one end and a hand grip at the opposite end, a lever 50 in ratchet connection with said stock intermediate the ends thereof and means adjacent said lever whereby a wrench or other lever may be applied to assist in imparting rotary motion to the said stock.

My invention further consists in the arrangement of the stock as above briefly de-

scribed, the nut engaging end of said stock being provided with a socket adapted to receive the uniform shanks of variously sized nut engaging cups and means upon said stock for securing said shanks within said socket.

My invention still further consists in the arrangement as thus briefly described, the said hand grip and the said lever being so arranged as to be easily and quickly detached from the said stock to facilitate packing or shipping the device.

My invention still further consists in the novel arrangement and combination of parts all as will be more fully described herein-after and particularly pointed out in the claims.

My invention will be more readily understood with reference to the accompanying drawings, in which—

Figure 1 is a side elevation of a wrench constructed in accordance with my invention, Fig. 2 is a section taken substantially upon the line $x-x$ of Fig. 1, Fig. 3 is a fragmentary section taken through the ratchet device longitudinally of the stock, the said stock being shown in elevation, Fig. 4 is an enlarged detail section taken substantially upon the line $y-y$ of Fig. 1, Fig. 5 is a section taken upon the line $z-z$ of Fig. 4, Fig. 6 is an end view of the stock employed in carrying out my invention illustrating the socket, Fig. 7 is an end view of a nut engaging cup adapted to be used in connection with my improved wrench, and Fig. 8 is a side elevation thereof.

Referring now more particularly to the drawing, 1 represents generally the stock forming a part of my invention. This stock 95 may be made in any desired length, and is shown in the present instance of such length as to be conveniently handled by the operator, and is of a diameter of such size as to allow of the insertion of the stock into 100 small spaces and yet which is sufficiently large to withstand the severe strains incident to devices of this character.

It is one of the principal objects of my invention to enable a wrench of this character to be employed in removing variously sized nuts, and to this end I provide in one end of the stock 1 a socket 2, which may be square, hexagonal or octagonal as desired to receive a correspondingly shaped shank 3 of 110 the nut engaging cup 4, a set screw or other securing means 5 being provided adjacent

the end of the stock to engage the inserted end 3 of the nut socket to prevent the same from becoming disengaged from the stock. By this means it is obvious that nut engaging cups of various sizes may be employed in connection with my wrench, the advantages of which are apparent. The opposite end of the stock 1 is provided with a suitable hand grip 6, removably secured to the stock 10 in any suitable way, a set screw 7 being employed in the present instance.

From the arrangement thus briefly described it is obvious that nuts positioned in corners or other places inaccessible to the ordinary wrench may be quickly and easily applied to or disengaged from the bolt.

In order that the necessary rotary motion may be applied to the stock, I provide intermediate the ends of said stock, a squared portion 8, which is adapted to be engaged by an ordinary monkey wrench or other suitable lever. A similar squared portion 9 is provided adjacent the squared portion 8, being separated therefrom by a narrow bearing surface 10 and a flange 11, the purposes of which will be more fully described later. The stock or body portion of the wrench is reduced in diameter as at 12 from the squared portion 9 to the end to which the hand grip 6 is attached, and is provided adjacent the said squared portion 9 with a threaded portion 13.

A lever 14 is employed in connection with the stock of my wrench to assist in applying rotary motion to the said stock, and in order that the stock may be rotated in opposite directions, necessary in applying or removing nuts from a bolt, the lever is in ratchet connection with the said stock and means is provided upon the lever for operating the ratchet mentioned to rotate the stock in the desired direction. In attaining this end the lever 14 is bifurcated, the bifurcations 15 and 16 being provided with openings, the opening in the bifurcation 16 being sufficiently large in diameter to pass over the squared portion 9 of the shank and rest upon the bearing surface 10 adjacent the flange 11 thereon. The opening in the bifurcation 15 is substantially smaller, and is adapted to be limited in its movement in one direction upon the stock by engagement with a shoulder 9' formed by the joining of the reduced end 12 of the stock with the squared portion 9. A pair of ratchet wheels 17 and 18, each provided with a squared bore as at 19 to fit over the squared portion 9 upon the stock, is provided and the said ratchet wheels are adapted to be held thereon between the bifurcated ends of the lever 14. It will be seen that by reason of the squared bores of the ratchet wheels engaging over the squared portion upon the stock that rotation imparted to the ratchet wheels will at once be transmitted to the said stock, and in order

that the lever 14 may be employed to supply this power, a pair of pawls 20 and 21 is provided, each pivoted at its intermediate portion to a pin 22 secured to the bifurcated end of the lever 14, and adapted at their outer extremities to engage the teeth of the ratchet wheels 17 and 18 respectively. The inner end of each pawl is provided with a transverse groove 23, within which the free end of a spring 24 is adapted to fit, in order that the pawls may be normally held in engagement with the teeth of the ratchet wheels. The ratchet wheels are provided with oppositely disposed teeth so that the pawls may be used selectively to engage the respective ratchet wheels in order that motion may be imparted to the stock in the desired direction.

The means employed in the present invention for selectively operating the pawls consists in the arrangement of a ring 25 upon the lever 14 and adjacent the inner ends of the pawls 20 and 21. The said ring is provided with a peripheral flange 26, substantially semi-circular in form and extending beyond the ring 25 a distance sufficient to engage over the ends of the pawls 20 and 21. Stops 27 and 28 are provided upon the lever 14 to limit the rotary movement of the selective ring 25. Referring to Fig. 4 of the drawings it will be seen that upon rotation of the ring 25 the inner ends of the spring pressed pawls will be engaged by the peripheral flange 26 to disengage the opposite end of the respective pawls from the teeth of their respective ratchet wheels. It is also obvious that the stops 27 and 28 provided upon the lever limit the rotation of the ring 25, and that the construction of the flange 26 permits only one of the pawls to be engaged with the respective ratchet wheels during the operation. A spacing member 29 is provided upon the lever 14 and extends outwardly between the bifurcated end of said lever to form a yoke 30, and by this construction the ratchet wheels and pawls are held in spaced relation to each other. It is preferred that the lever be so arranged as to permit of the same being detached when not in use so as to occupy but little space in a tool kit or other receptacle, and in accomplishing this end the said lever is in sections. The handle portion 14 forms one section while the bifurcated portion forms another, the inner end of the bifurcations 15 and 16 and of the spacing member 29 being formed into a common head 30 in any suitable manner and provided with a threaded extension 31 for engagement with a socket 32 formed in the end of the lever 14. The adjacent end of the lever 14 is enlarged or flared as at 33 to be larger in diameter than the head 30 of the bifurcated section, and the annular shoulder formed by the outwardly extending 130

enlarged portion 33 of the lever forms a suitable seat for the ring 25 constituting the pawl controlling device. When the bifurcated end of the lever, carrying the ratchet wheels and pawls in engagement therewith is positioned properly upon the stock, a washer nut and lock nut 34 and 35 respectively are then placed in position over the threads 13 of the stock in order that the said lever may be held securely against displacement.

It is obvious from the construction that a device arranged in accordance therewith will prove of great value to the mechanic, as the wrench may be used to manipulate nuts so positioned as to be inaccessible to the ordinary wrench, the arrangement of the nut engaging cups also being of particular advantage, as with the standard sized shank adapted to fit within the socket in the end of the stock, the nut engaging portion may be made to fit any sized nuts and still be applicable to the wrench.

From the description the operation of the operating lever through the pawl and ratchet connections with the stock is obvious, and should it be necessary to apply more power to the stock than is capable of being applied through the lever, a wrench or other lever may be applied to the squared portion 8 to assist in rotating the stock. The arrangement of the ratchet lever in connection with the stock enables the said stock to be held securely over the nut while the few turns of the stock are being made preparatory to applying greater power in tightening the nut upon the bolt, or in others, the tool may be readily held in position by means of the lever 14 while the nut is being turned by means of the grip 6.

I claim:—

1. A wrench comprising a stock provided at one end with nut engaging means and at its opposite end with a hand grip, said stock being provided intermediate its ends with a squared portion, said stock being reduced in diameter from one end of said squared portion to said hand grip, and provided adjacent the opposite end of said squared portion with a bearing surface, a lever provided with a bifurcated end, said bifurcations provided with apertures adapted to fit upon said bearing surface and upon the reduced stock portion adjacent said squared portion respectively, a pair of ratchet wheels, each provided with a squared bore and oppositely disposed teeth, said wheels being adapted to fit upon said squared por-

tion between the bifurcated end of said lever, a spacing member secured to said lever and extending between said ratchet wheels for holding the same in spaced relation, a pair of pawls secured upon said lever and coöperating with said ratchet wheels, selective means for operating said pawls, and means for holding said lever in position upon said stock, substantially as described.

2. A wrench comprising a stock provided at one end with means for engaging a nut and at its opposite end with a hand grip, said stock intermediate its ends being provided with a squared portion, a bearing surface on each side of said squared portion, one of said bearing portions being in diameter equal to the diagonal of the squared portion, and the other bearing surface being in diameter equal to the diameter of said squared portion, a flange on said stock beyond the larger bearing portion and said stock being threaded adjacent the smaller portion; ratchet wheels mounted upon said squared portion, a lever rotatably mounted upon said bearing portions, means connecting said ratchet wheels with said lever, and a nut for engagement with said threads, substantially as described.

3. A wrench comprising a stock provided at one end with means for engaging a nut and at its opposite end with a hand grip, said stock intermediate its ends being provided with a squared portion, a bearing surface on each side of said squared portion, one of said bearing portions being in diameter equal to the diagonal of the squared portion and the other bearing surface being in diameter equal to the diameter of the squared portion, a flange on said stock beyond the larger bearing portion and said stock being threaded adjacent the smaller portion; ratchet wheels mounted upon said squared portion, a lever provided with bearing sockets for engagement over said large and small bearing portions respectively beyond said ratchet wheels, means connecting ratchet wheels with said lever, and a nut for engagement with said threads for retaining said lever and ratchet wheels in position upon said stock, substantially as described.

In testimony whereof I have signed my name to this specification in the presence of two subscribing witnesses.
